UNITED STATES PATENT OFFICE.

LINUS TERRY FURNAS, OF LIMA, OHIO.

DRESS-FORM.

No. 888,992.

Specification of Letters Patent.

Patented May 26, 1908.

Application filed August 28, 1907. Serial No. 390,464.

To all whom it may concern:

Be it known that I, LINUS TERRY FURNAS, a citizen of the United States, and a resident of Lima, in the county of Allen and State of Ohio, have invented a new and useful Improvement in Dress-Forms, of which the following is a full, clear, and exact description.

The purpose of the invention is to provide an article of female apparel adapted to be worn beneath the skirts and to extend partially around the figure, being supported from the waist, and the object of the article is to provide means for rectifying deficiencies in the human figure, particularly at the hips and back, and also to provide an article of the character described adaptable to all conditions and to all persons.

It is another purpose of the invention to provide an article of the character mentioned that can be expeditiously and conveniently adjusted in any way desired, or that the figure may require. If the hips are small, a proper fullness can be directed to the sides, and should the back be flat, the fulness can be directed to that point, and it is also a purpose of the invention to so construct the article that the members are graduated in such manner that when adjusted and the article worn, its presence cannot be detected; and further, to so construct the article that it can be stretched flat and washed without removing any of its elements.

The invention consists in the novel construction and combination of the several parts as will be hereinafter fully set forth and pointed out in the claims.

Reference is to be had to the accompanying drawings forming a part of this specification, in which similar characters of reference indicate corresponding parts in all the figures.

Figure 1 is a rear elevation of the article as it appears upon the person; Fig. 2 is an inner face view of the adjusted article laid flat; Fig. 3 is an outer face view of the article laid perfectly flat, none of its members having been adjusted; Fig. 4 is an inner face view of the article, its members being in the same condition as shown in Fig. 3; and Fig. 5 is a transverse section through the article.

The article in its entirety is made of fabric of any suitable description, preferably a washable fabric. The body portion A of the article is of sufficient length after being adjusted to partially encircle the waist of the wearer and it is provided with a straight

upper edge 10, and a convexed lower edge 11, as is best shown in Fig. 4, and at the upper portion of the body at each end, tie strings 11^a are secured which are adapted to be brought together at the front of the person and suitably connected, as is shown at 12 in Fig. 1. At the bottom edge of the body A, a flounce B is secured extending from end to end of the said body section, and having practically the same general contour.

In addition to the lower or edge flounce B, a series of overlapping body flounces are provided; these body flounces extend also from end to end of the body and have their lower edges convexed, the lower edge of the upper flounce being less convexed than the corresponding edges of other flounces. These body flounces commencing from the top, are designated respectively as B', B², B³, B⁴, and B⁵. In addition to these body flounces just named that extend from end to end of the body A, an auxiliary and shorter flounce B⁶ is provided, which is partially covered by the flounce B⁵, and rests upon the flounce B.

The auxiliary flounce B⁶ extends an equal distance from the center of the article and terminates some distance from the ends thereof, as is clearly shown in Fig. 3. Where the various body flounces connect, with the body A, a hem is formed at their upper edge; these hems commencing from the top of the article are designated respectively as 14, 15, 16, 17, 18, and 19, and the hem for the short or auxiliary flounce B⁶ is designated as 20. The flounces are all located upon the outer face of the body and at the inner face of the body openings 21 and 22 are located at each side of the center, being produced in the aforesaid hems, and the said openings 21 and 22 for all of the hems are in vertical alinement, as is shown clearly in Fig. 4. Two tapes or draw strings are employed for each hem, and they are secured in any suitable or approved manner at the outer end portions of the hems, as is shown at 23 in Fig. 4, and the inner or free ends of these draw strings or tapes are made to pass out at the rear of the article through the openings 21 and 22 in the respective hems. The draw strings or tapes are designated as follows: Those for the hem 14, as 14^a, and 14^b, those for the hem 15, as 15^a and 15^b, and the remaining sets of free ends of said draw strings are designated respectively as 16^a, 16^b, 17^a, 17^b, 18^a, 18^b, 20^a, and 20^b, and 19^a and 19^b.

In adjusting the form to the figure, the

mating strings are drawn up and tied as may be required, and the operation will be hereinafter more particularly set forth. When the article has been adjusted to be fitted to the figure the back of the article will have the shirring effect shown at C in Fig. 2, while the front of the article will have the plaited effect shown at C' in Fig. 1, and it may be here remarked that a plait 24 is formed in each flounce in its central portion transversely on the flounce so as to insure the flounce having a segmental shape when worn, and also to insure the article fitting snugly to the figure. The end portions of the completed article are quite thin and the lower edge of the edge flounce B is also quite thin since this flounce is of a single thickness and is not covered by any of the others.

It is evident that the construction of the article admits of a flounce being thrown in every possible direction that any figure may need; it can be made light in the back and heavy on the sides, or it may be made heavy on the back and light on the sides, or it can be made medium at the back and the sides. By releasing the tapes a little the flounces can be thrown practically over the hips, or by drawing the tapes more or less tightly the flounces can be thrown practically in the back making the effect heavy at that point, in fact there is no ordinary figure that cannot be easily and quickly corrected by means of the described article.

It is also apparent that the article is tapered off with practically a feather edge both at the sides and at the bottom whereby the outline of the article is not visible, a defect common to most all such articles of apparel; furthermore it is evident that it can be made perfectly flat for washing and that at such time all the tapes remain in position so that all that is necessary is to draw the tapes up and tie them, whereupon the article is ready to be worn again.

Having thus described my invention, I claim as new and desire to secure by Letters Patent,—

1. As an improved article of manufacture, an adjustable dress form constructed wholly of a pliable material and consisting of a body section, and a series of over-lying flounces secured on the face of the body section, each flounce at this point of engagement with the body being provided with a hem, and draw strings within the hems secured at their outer ends, their free ends being passed out through the body at its central portion as described.

2. As an improved article of manufacture,

an adjustable dress form constructed wholly of fabric and comprising a body section having a straight upper and curved lower edge, a series of over-lapping flounces upon the outer face of the body shaped correspondingly to the body and attached thereto at their upper edges by means of hems, and pairs of tapes in each hem, said tapes being secured to the body at their outer ends, their inner ends being passed loosely out through the back of the body rendering the article adjustable to any desired thickness or form, as described.

3. A dress form constructed of fabric and consisting of a body section of a series of adjustable over-lying flounces of corresponding shape to that of the body secured to the outer face of the body and extending from end to end, and a pair of draw strings in each flounce mainly concealed by the flounce and having their outer ends fast at the outer ends of the body and their inner ends loosely passed through the back of the body at its central portion.

4. A dress form constructed of fabric and consisting of a body section of approximately segmental shape, a series of over-lying flounces of corresponding shape to that of the body secured at their upper edges to the outer face of the body, extending from end to end, with the exception of a lower flounce which extends a short distance each side of the center of the body, a single flounce at the lower edge of the body also extending from end to end, and a pair of draw strings in each flounce, which strings are secured at their outer ends to the outer end portions of the body, their inner ends being passed out through the back central portion of the body.

5. A dress form, comprising a body, a plurality of flounces having hems at their upper edges and secured at said edges upon the outer face of the body one below the other, and draw strings in the hems of the flounces.

6. A dress form, comprising a plurality of connected and overlying flounces of pliable material, and a pair of draw strings for each flounce, each string being secured at one end in the flounce and having its other end extending out through the flounce.

In testimony whereof I have signed my name to this specification in the presence of two subscribing witnesses.

LINUS TERRY FURNAS.
